LINWOOD G. WHITNEY, OF NEW YORK, N. Y., ASSIGNOR TO WHITNEY DUPLICATING CHECK COMPANY, OF NEW YORK, N. Y., A CORPORATION OF NEW YORK.

MANIFOLD ORDER OR SALES BOOK.

933,513.

Specification of Letters Patent. Patented Sept. 7, 1909.

Application filed June 9, 1909. Serial No. 501,117.

To all whom it may concern:

Be it known that I, LINWOOD G. WHITNEY, a citizen of the United States, and a resident of New York city, in the county of New 5 York and State of New York, have invented certain new and useful Improvements in Manifold Order or Sales Books, of which the following is a specification.

The invention relates to improvements in 10 manifold and order sales-books, and it consists in the novel features, structure and combinations of parts hereinafter described, and particularly pointed out in the claims.

The object of the invention is to provide 15 a very compact and convenient order or sales-book of durable character adapted, among other purposes, for use by salesmen in taking orders for goods sold and by waiters in hotels, restaurants and the like.

20 The sales-book of my invention, in its preferred embodiment, comprises two hinged backs or cover-sections in line with each other, a set of independent original order slips loosely hinged on rings at the upper edge of the lower cover-section and adapted to be turned on said rings to lie upon the upper section or the lower section at will, a plate of metal or any suitable material hinged at its left hand edge to the left 25 hand edge of the lower or back cover-section and adapted to lie on said section or be turned laterally toward the left on its hinges from over said section, a carbon holder on the upper edge of said plate for holding one 30 or more sheets of carbon paper, and a set or bank of duplicate order slips secured at their lower ends in a hinged manner on rings at the lower edge of said plate and adapted to lie on said plate or be turned on said rings 35 from over the same, the entire set of duplicate order slips being capable of being turned downwardly from over said plate without any thereof being bent or folded and also capable with said plate of being 40 turned to the left from over the back cover-section of the book. I preferably provide two sheets of carbon paper so that two duplicate order slips may be prepared by writing on one original order slip. The relation of 45 the parts of the book is such that, as required, some of the original order slips may be housed below the plate supporting the duplicate order slips and others extended upon the upper cover-section, while any one

of the original slips may be on top of the 55 duplicate slips and against the top carbon sheet by which the transfer is made to the duplicate slip of the writing made on the original slip.

The invention will be fully understood 60 from the detailed description hereinafter presented, reference being had to the accompanying drawings, in which:

Figure 1 is a top view, partly broken away, of an order book embodying the invention, the book being shown in its open position, with the top cover-section turned upwardly and all of the original order slips except the top one housed below the plate supporting the set of duplicate slips and 65 said upper original slip being shown upon the set of duplicate slips and denoting by the writings thereon that it has been used in connection with the duplicate slips; one corner of the exposed original order slip 70 is shown as having been turned over for the purpose of exposing the carbon sheet below the same; Fig. 2 is a longitudinal section, partly broken away, through the same on the dotted line 2—2 of Fig. 1, the cover-sections being shown in Fig. 2 in their closed position; Fig. 3 is a top view, on a reduced scale, of the open book presented in Fig. 1, the original order slip shown exposed in Fig. 75 1 being illustrated in Fig. 3 as having been turned over against the upper cover-section and one sheet of the carbon being shown as turned upwardly to expose the duplicate check below it and said check being illustrated as partly torn away to expose the 80 carbon sheet below it; the dotted lines in Fig. 3 illustrate the plate carrying the bank of duplicate order slips as having been turned to the left from over the back cover-section of the book; Fig. 4 is a detached top 85 view, partly broken away, of the carbon holder, with a portion of the plate which supports the duplicate order slips, the clamping member of said holder being shown in a partly open position; Fig. 5 is a like view, 90 of the same with the clamping member of the holder shown in section and in its closed position, and Fig. 6 is an enlarged longitudinal section through the carbon holder and adjacent portions of the book and is 95 presented to illustrate the manner of threading the upper end portions of the carbon sheets through slots in the plate supporting 100 105

the duplicating order slips, the clamping member of the holder being shown in its closed position.

In the drawings, 15 designates the lower or back cover-section, 16 the upper or top cover-section, 17 a back-section connecting, in a hinged manner, said upper and lower cover-sections, 18 a set of original order slips, 19 a set of duplicate order slips, 20 a plate supporting said duplicate order slips, 21 an upper carbon sheet to lie upon the upper duplicate order slip with its transfer surface facing downwardly against the same, 22 a second carbon sheet adapted to lie between the upper and next adjacent duplicate order slips with its transfer surface facing downwardly against said adjacent slip, 23 rings secured to the upper portion of the lower cover section and freely receiving in a hinged manner the said original order slips, 24 rings secured to the lower portion of the plate 20 and freely receiving in a hinged manner the said duplicate order slips, and 25 the hinge by which said plate 20 is secured at its left hand edge to the left hand edge of the lower cover-section. The original order slips 18 are perforated and strung on the rings 23, and the duplicate order slips 19 are perforated and strung on the rings 24. The original order slips 18 and duplicate order slips 19 will be suitably lined or spaced and bear such data as may be required, in accordance with the nature of the business in which the book may be used and these features will, of course, necessarily vary as circumstances and conveniences may suggest, and form no part of the present invention. The rings 23, 24 correspond with each other and each comprises a lower U-shaped section 26 and an upper swivel-section 27 (Fig. 2) which may be opened and closed, at will, to admit and retain the order slips.

In the construction of the back cover-section 15 I make use of a metal plate 28 covered with leather or other suitable material and of about the size desired for the cover-section. The plate 28 stiffens the back cover-section and enables it to form a durable support for the use of a salesman in writing on the checks, said back cover-section being usually held in one hand while the salesman is writing on the checks with his other hand. The upper end of the plate 28 receives the rings 23, and said plate is slotted to receive the lower edges of the rings and grooved upwardly and downwardly at opposite sides of the rings, as shown in Fig. 1, to receive a pin 29, which extends through the grooved portions of the plate and through apertures in the lower edge portions of the rings. The plate 28 may be of aluminum and the upward grooves pressed in it adjacent to the rings 23 create upwardly curved sections 30 below which the pin 29 passes and the down-

wardly pressed grooves 31 create downwardly curved sections in which the pin 29 has a bearing, the pin 29 thus passing below the upwardly curved section 30 and upon the downwardly curved sections formed by the grooves 31. When the rings 23 are seated in slots in the plate 28 and the pin 29 has been passed through them, the rings become detachably held in position and do not occupy unnecessary space in the book.

In Letters Patent granted to me on August 25, 1908, No. 897,245, I illustrate rings, numbered 22 in said patent, corresponding with the rings 23 of the present application, but the rings in said patent are not secured in a plate 28 constituting the main member of the back cover-section, but on a separate narrow folded plate.

The original order slips or checks 18 strung on the rings 23 may all be housed below the plate 20 or they may all be turned on the upper opened cover-section 16 and any one of said checks or slips may be placed on the pad of duplicate order slips 19 in the manner fully explained in my aforesaid Letters Patent.

The plate 20 is preferably of aluminum and secured at its left hand edge to the left hand edge of the plate 28 by means of the hinges 25, and that part of the structure 95 comprised in the plates 20, 28 is of very durable character, the same being of metal and the knuckles of the hinges 25 being integral with said plates and of considerable length so as to avoid any twisting action of the 100 plate 20. The hinges 25 permit the plate 20 to be turned to the left from over the cover-section 16 in the manner indicated by the dotted lines in Fig. 3, thus exposing said cover-section to receive the original order 105 slips 18. The material of the hinges 25 affords a space between the facing surfaces of the plate 20 and cover-section 15 adapted to conveniently house the original slips 18 and allow the plate 20 to lie flat on said slips.

At its upper end the plate 20 is formed with two parallel transverse slots 32, 33, respectively (Figs. 5 and 6), through which the upper ends of the two carbon sheets 21 and 22 are strung or threaded, said ends of said sheets being first passed downwardly through the slot 32 and then returned upwardly through the slot 33. The carbon sheets 21, 22 are locked in position by means of a clamp 34 preferably formed of aluminum and pivotally secured, at 35, to the plate 20. The clamp 34 is a plate of metal folded upon itself and adapted to pass rather closely on the end of the plate 20 and folded end portions of the carbon sheets, as shown on an enlarged scale in Fig. 6. When the clamp 34 is in its closed position, shown in Figs. 5 and 6, the carbon sheets become locked at their upper ends and when the clamp 34 is turned outwardly on its pivot, 130

the slots 32, 33 become exposed and the carbon sheets may be removed and conveniently renewed. In order to lock the clamp 34 in its closed position, I provide the plate 20 with a small stud 36 and the upper leaf of the clamp 34 with the hole 37 adapted on the closing of the clamp to snap over and interlock with said stud.

The rings 24 are detachably secured to the lower end of the plate 20 in the same manner that the rings 23 are secured to the upper end of the plate 28, the lower members of said rings 24 being seated in slots 38, indicated by dotted lines in Fig. 3, and there held by a pin 39 passing through oppositely formed grooves 40, 41 corresponding exactly with the grooves indicated in Fig. 1 as receiving the pin 29.

In the employment of the book hereinbefore described, the original checks or order-slips 18 will initially be disposed below the plate 20, and the upper carbon sheet 21 will lie on the upper duplicate check or order-slip 19, while the carbon sheet 22 will lie between the said upper duplicate order-slip and the order-slip next below the same. Thereupon in the use of the book the front cover-section 16 will be opened and the salesman will turn the plate 20 carrying the duplicate order-slips to the left and then turn the top original check upwardly against the cover-section 16, whereupon the plate 20 will be returned to its position over the section 15 and the said original order-slip which had been turned upwardly against the cover-section 16 will be turned downwardly to lie upon the top carbon sheet 21 in the position shown in Figs. 1 and 2. The said original order-slip thus exposed and which for special identification I number 50 may be written on and the writing will transfer through to the upper and next adjacent duplicate order-slips 19, which may then be removed or allowed to remain on the rings 24. The original check 50 written on may also be allowed to remain on its rings 23 if desired, since with the construction shown any one of the original order-slips may be placed on the top carbon sheet, so that the original order-slips 18 may be used one after another in succession and allowed to remain on the rings 23 or said slips may be used in any order desired without detaching them from said rings. For illustration, if it should be desired to use one of the middle order-slips 18, it would simply be necessary to throw the upper half of the set of original order-slips against the cover-section 16 so that the order-slip required might be exposed and placed on the set of duplicate order-slips. The duplicate order-slips may also be used one after another in succession or in almost any other order desired, and they all may be left on the rings 24, if desired, and may be turned back under the

carbon sheets as frequently as it might be desired to add to orders already taken. For illustration, if it should be desired to add to the order represented in Fig. 1, after said order had been apparently closed and other 70 duplicate order-slips made use of, the two duplicate order-slips represented as in use in Fig. 1 may be restored to their position below the two carbon sheets and the original order slip, shown in Fig. 1, restored to its 75 position and thereupon any additional data could be added to the original order-slip and transferred to the two duplicate order-slips.

I do not limit my book to the use of two 80 carbon sheets 21, 22, since I will only use two carbon sheets when two duplicates of the order are desired. When only one duplicate is necessary, only one carbon sheet will be made use of.

The present invention embraces certain improvements on the book shown in my aforesaid Letters Patent No. 897,245, dated August 25, 1908. In the said patent I show a carbon holder plate and a set of duplicate 90 order-slips as strung on rings at the left hand edge of the bottom cover-section. I have discovered, however, that the carbon holder plate supporting the duplicate checks must be hinged in a very firm manner to the bottom cover-section, so as to prevent any swiveling or twisting action of said holder plate, and in the present instance I firmly hinge the plates 20, 28 together and freely hinge the duplicate order-slips to the carbon 100 holder plate by the rings 24, thus independently hinging the carbon holder plate and duplicate order-slips.

In some uses of the book it may be desirable to hinge the duplicate order-slips at their left hand edge to the left hand edge portion of the carbon holder plate 20 in lieu of at the lower edge of said plate, and to provide for such hinging of the duplicate order-slips I construct the plate 20, as shown 105 by the dotted lines in Fig. 3, with slots 42 and grooves 43, so as to enable the transfer of the rings 24 and pin 39 from the lower edge to the left hand edge of said plate 20.

What I claim as my invention and desire 110 to secure by Letters Patent, is:

1. A manifold sales-book comprising a back-section, a set of original order-slips secured at the upper end thereof, a plate hinged at its left hand edge to the left hand edge of said back-section so as to be swung from off said section, a set of duplicate order-slips mounted on and hinged to said plate, and a carbon sheet on said duplicate 120 slips, said original order-slips being secured by means adapting them, without detachment, to be independently placed on said carbon sheet on the duplicate order-slips; substantially as set forth.

2. A manifold sales-book comprising a 130

back-section, a set of original order-slips secured at the upper end thereof, a plate hinged at its left hand edge to the left hand edge of said back-section so as to be swung from off said section, a set of duplicate order-slips mounted on and hinged at their lower ends to the lower end of said plate, and a carbon sheet on said duplicate slips, said original order-slips being secured by 5 means adapting them, without detachment, to be independently placed on said carbon sheet on the duplicate order-slips; substantially as set forth.

3. A manifold sales-book comprising a metal plate 28, a set of original order-slips secured at the upper end of said plate, a metal plate 20 normally over and hinged at its left hand edge to the left hand edge of said plate 28, a set of duplicate order-slips 10 mounted on and hinged to said plate 20 so as to be swung from off the same, and a carbon sheet on said duplicate slips, said original order-slips being secured by means adapting them, without detachment, to be independently placed on said carbon sheet 15 on the duplicate order-slips; substantially as set forth.

4. A manifold sales-book comprising a metal plate 28, a set of original order-slips secured at the upper end of said plate, a metal plate 20 normally over and hinged at its left hand edge to the left hand edge of said plate 28, a set of duplicate order-slips 20 mounted on and secured at their lower ends to the lower end of said plate 20, and a carbon sheet on said duplicate slips, said original order-slips being secured by means adapting them, without detachment, to be independently placed on said carbon sheet 25 on the duplicate order-slips; substantially as set forth.

5. A manifold sales-book comprising a back-section, a set of original order-slips secured at the upper end thereof, a plate hinged at its left hand edge to the left hand edge of said back-section so as to be swung from off said section, a set of duplicate order-slips mounted on and hinged to said plate, and a carbon sheet on said duplicate 30 slips, said original order-slips being secured by means adapting them, without detachment, to be independently placed on said carbon sheet 35 on the duplicate order-slips, and said plate being provided with rings on 40 which said duplicate slips are strung; substantially as set forth.

6. A manifold sales-book comprising a back-section, a set of original order-slips secured at the upper end thereof, a plate hinged at its left hand edge to the left hand edge of said back-section so as to be swung from off said section, a set of duplicate order-slips mounted on and hinged to said plate, and a carbon sheet on said duplicate 45 slips, said original order-slips being secured

by means adapting them, without detachment, to be independently placed on said carbon sheet on the duplicate order slips, and said plate being slotted at its upper end to receive the upper end of said carbon sheet 70 and provided with a folded pivoted plate clamp to engage the opposite faces of the end of said plate and secure said sheet; substantially as set forth.

7. A manifold sales-book comprising a back-section, a set of original order-slips secured at the upper end thereof, a plate hinged at its left hand edge to the left hand edge of said back-section so as to be swung from off said section, a set of duplicate order-slips mounted on said plate, and a carbon sheet on said duplicate slips, said plate having a plurality of slots at its upper end through which said sheet may be threaded and provided with a folded pivoted plate 80 clamp to engage the opposite faces of the end of said plate and secure said sheet; substantially as set forth.

8. A manifold sales-book comprising a back-section, a set of original order-slips secured at the upper end thereof, a plate hinged at its left hand edge to the left hand edge of said back-section so as to be swung from off said section, a set of duplicate order-slips mounted on and secured at 90 their lower ends to the lower end of said plate, and two carbon sheets carried by said plate for use in transferring one original writing on an original slip to two duplicate slips, said plate having a plurality of 95 slots at its upper end through which said sheets may be threaded and provided with a folded pivoted plate clamp to engage the opposite faces of the end of said plate and secure said sheets; substantially as set forth. 100

9. A manifold sales-book comprising cover-sections hinged together, a set of original order-slips secured on the upper end of the back cover-section by means adapting them to be turned to lie upon either of said sections when the front-section is opened from the back-section, a plate hinged at its left hand edge to the left hand edge of said back-section so as to be swung from off the same, a set of duplicate order-slips mounted 110 on and hinged at one edge to said plate, and a carbon sheet on said duplicate order-slips; substantially as set forth. 115

10. A manifold sales-book comprising cover-sections hinged together, a set of original order-slips secured on the upper end of the back cover-section by means adapting them to be turned to lie upon either of said sections when the front-section is opened from the back-section, a plate hinged at its left hand edge to the left hand edge of said back-section so as to be swung from off the same, a set of duplicate order-slips mounted 120 on and hinged at their lower ends to the lower end of said plate, and a carbon sheet 125

on said duplicate order-slips; substantially as set forth.

11. A manifold sales-book comprising cover-sections hinged together, a set of original order-slips secured on the upper end of the back cover-section by means adapting them to be turned to lie upon either of said sections when the front-section is opened from the back-section, a plate permanently hinged at one edge to one edge of said back-section so as to be swung from off the same, a set of duplicate order-slips mounted on said plate, means secured to and carried by said plate for detachably receiving in a hinged manner said set of duplicate order-slips whereby said set becomes secured at one edge to said plate, and a carbon sheet on said duplicate order-slips; substantially as set forth.
12. A manifold sales-book comprising

cover-sections hinged together, a set of original order-slips secured on the upper end of the back cover-section by means adapting them to be turned to lie upon either of said sections when the front-section is opened 25 from the back-section, a plate hinged at one edge to one edge of said back-section so as to be swung from off the same, a set of duplicate order-slips mounted on and secured at their lower ends to the lower end of said 30 plate, and a carbon sheet on said duplicate order-slips; substantially as set forth.

Signed at New York city, in the county of New York and State of New York, this 7th day of June A. D. 1909.
